DENTAL WATER GUN

Corless W. Wiley, 1505 Junior Drive,
Dallas, Tex. 75208

Filed Apr. 17, 1974, Ser. No. 461,541

Term of patent 14 years

Int. Cl. D24—02

U.S. Cl. D24—1 D

FIG. 4

FIG. 3

FIG. 1

FIG. 2

FIG. 1 is a front perspective view of a dental water gun showing my new design;

FIG. 2 is a side elevation thereof;

FIG. 3 is a top plan view thereof; and

FIG. 4 is a bottom plan view thereof.

I claim:

The ornamental design for a dental water gun, as shown and described.
